UNITED STATES PATENT OFFICE.

OTTO J. WYLER AND DAVID C. REIDY, OF DOUGLAS, ARIZONA TERRITORY.

SWITCH.

No. 921,051.

Specification of Letters Patent.

Patented May 11, 1909.

Application filed January 12, 1909. Serial No. 471,965.

To all whom it may concern:

Be it known that we, OTTO J. WYLER and DAVID C. REIDY, citizens of the United States, residing at Douglas, in the county of 5 Cochise and Territory of Arizona, have invented certain new and useful Improvements in Switches, of which the following is a specification, reference being had therein to the accompanying drawing.

10 This invention relates to switches, and has for its object the provision of means for lengthening the life of switch points and using again the points that have become worn out on the curve side of the switch.

15 Another object of this invention is the production of a switch lever or bridle bar which insures the complete opening and closing of a switch.

With these and other objects in view, this 20 invention consists of certain novel constructions, combinations, and arrangements of parts, as will be hereinafter fully described and claimed.

In the drawings: Figure 1 is a plan view of 25 the switch showing the operating lever in connection therewith. Fig. 2 is a sectional view taken on line 2—2 Fig. 1. Fig. 3 is a detail perspective of the lever member.

Referring to the drawings by numerals, 1 30 designates the main rail of the main track, and 2 designates the main rail of the side track. A short-point rail 3 and a long-point rail 4 are connected to each other by means of a lever member or bridle bar 5, which lever 35 member comprises a primary parallel portion 6 and an auxiliary parallel portion 7, which are connected by means of an integral angularly-disposed portion 8. The lever member or bridle bar 5 is positioned un-

40 der the main rails 1 and 2 and is connected near the points or ends of the short-point rail 3 and the long-point rail 4 by means of angle plates 9. By having the lever member 5 so positioned under the main rails 1 and 45 2, it will be obvious that the short-point rail 3 and the long-point rail 4 will not be allowed any upward movement. The lever or bridle bar 5 consists of a substantially Z-shaped member, and it will be obvious that,

50 by having the same formed in one piece, it will greatly reduce the cost of the same, and will last considerably longer than if the same was made of several sections and connected together. The switch, by means of the lever member of bridle bar 5, may be operated

by any switch-throwing mechanism, as indicated by 10.

The main rail 2 of the side track comprises a portion 11 which extends parallel with the main rail 1 of the main track, and an angularly-disposed or bent portion 12. The short-point rail 3 is provided with a beveled point 13, which is adapted to engage the angularly-disposed portion 12 of the rail 2, at a considerable distance back of the point 65 where said rail curves or is disposed at an angle to the parallel portion 11. The point 13 is adapted to so engage the rail 2 as to be to one side, or inside of an imaginary line drawn parallel with the tread of the longitudinally-extending portion 11 of the rail 2. A guard-rail 14 is positioned beside the parallel portion 11 of the rail 2 to prevent the rapid wearing out of point on rail 4.

It will be seen that, by using such a switch-lever or bridle bar, the same can be easily adjusted to the ends of the long-point rail and the short-point rail, and in case the ends should become worn, the lever can be moved back and the points sharpened, thus overcoming the necessity of placing an entirely new rail upon the switch. It will also be obvious that, by using a one-piece lever, comprising two parallel portions connected by an integral angle portion, when the switch is 80 thrown, the pressure will not be directly upon the point of rail 4 but at some distance back thereof, the said guard-rail 14 being so located as to prevent wheels from wearing point on long-point rail 4 as above indicated. 90

What we claim is:

1. In a switch, the combination with a long-point rail and a short-point rail, of a lever member, said lever member comprising a plurality of outer, parallel portions integrally 95 connected at their inner ends by an intermediate portion, disposed at an angle to the longitudinal axis of the parallel portion, and means securing said lever member to the ends of the long-point rail and the short point rail. 100

2. In a switch, the combination with a short-point rail and a long point rail, the point of said long-point rail extending beyond the end of said short-point rail, of a one-piece lever member, said lever member comprising a longitudinally-extending portion terminating in an angle portion, and said angle portion terminating in a longitudinally-extending portion parallel with said first-mentioned longitudinally-extending portion, and 110

angle plates secured to said lever-member and to said rails, for the purpose specified.

3. In a switch, the combination with a main track and a side track, of a short-point rail and a long-point rail, the main rail of the side track provided with an angularly-disposed or curved portion, the end of said long-point rail beveled on both sides and adapted to engage the tread of the main rail of the 10 curved or angularly-disposed portion so as to allow said end to be to one side of an im-

aginary line drawn along the inside of the tread of the parallel portion of the main rail of the side track.

In testimony whereof we hereunto affix 15 our signatures in presence of two witnesses.

OTTO J. WYLER.
DAVID C. REIDY.
